UNITED STATES PATENT OFFICE

102,178

DESIGN FOR A PERFUME BOTTLE OR SIMILAR CONTAINER

Burtis J. Dolan, Chicago, Ill., assignor to Lucien Lelong Inc., Chicago, Ill., a corporation of Illinois

Application July 18, 1936, Serial No. 64,167

Term of patent 3½ years

To all whom it may concern:

Be it known that I, Burtis J. Dolan, a citizen of the United States and a resident of the city of Chicago, county of Cook, and State of Illinois, have invented a new, original, and ornamental Design for a Perfume Bottle or Similar Container, of which the following is a specification, reference being had to the accompanying drawing, forming a part thereof.

On the drawing:

I claim:

The ornamental design for a perfume bottle or similar container, as shown.

BURTIS J. DOLAN.
